UNITED STATES PATENT OFFICE.

DAVID A. RUNNION, OF FORTRESS MONROE, VIRGINIA.

POCKET FLASH-LIGHT.

1,321,153.

Specification of Letters Patent.

Patented Nov. 11, 1919.

Application filed March 8, 1919. Serial No. 281,479.

To all whom it may concern:

Be it known that I, DAVID A. RUNNION, a citizen of the United States, residing at Fortress Monroe, in the county of Elizabeth 5 City and State of Virginia, have invented certain new and useful Improvements in Pocket Flash-Lights, of which the following is a specification.

This invention relates to electric lamps 10 adapted to be carried in the pocket; and it consists in the novel construction and combination of the parts hereinafter fully described and claimed which specially adapt the lamp for use in connection with a writing tablet or other similar article, inclosed 15 in the lamp casing.

In the drawings, Figure 1 is a side view, partially in section, of the casing of a lamp constructed according to this invention. 20 Fig. 2 is a similar view but shows the cover opened to expose the writing tablet. Fig. 3 is a front view of the parts shown in Fig. 2. Fig. 4 is a front view of the parts inside the casing, the inner cover or hand plate being raised. Fig. 5 is a detail view 25 of the switch.

The body portion 2 of the casing is preferably formed of thin sheet metal, and is rectangular in shape. An inner cover or 30 hand plate 3 is pivoted to the front edge of the top or end 4 of the body portion by a hinge 5. This hand plate 3 has side flanges 6 which stiffen it, and which fit between the sides of the body portion when the hand 35 plate is closed down, and which rest on stops 7 on the sides of the body portion, so as to afford a firm rest or support for the hand in writing.

An outer cover 8 is provided, and has 40 arms 9 on the upper end portions of its sides, which are pivoted to the middle parts of the sides adjacent to the top 4 of the body portion. These arms 9 straddle the body portion, and the outer cover has side flanges 45 which stiffen it and which fit down over the sides of the body portion.

The outer cover has a spring latch 10 of any approved construction for securing it to the body portion so as to prevent it 50 from opening accidentally.

A reflector and lamp socket 12 is secured to the middle part of the body portion, and 14 is an electric light bulb secured in the said socket. A battery 15 of any approved 55 make is arranged in the body portion of the casing, and is operatively connected with

the electric light bulb and provided with a switch of any approved construction for controlling the light.

A writing tablet 16, or other similar 60 memorandum pad, sheet, time-table, mirror, or other article which requires to be illuminated by the lamp, is attached to the inside of the outer cover. The writing tablet shown consists of a series of sheets of 65 paper having a metallic binder 17 at the upper end, and this binder has a hole 18 which engages detachably with a hook 19 on the outer cover, so that the writing tablet is prevented from being accidentally de- 70 tached from the cover, but can be removed and replaced as often as necessary.

The inner cover or hand plate 3 preferably has a recess 23 in its face, to accommodate the front portion of the writing 75 tablet. When the outer cover is closed the writing tablet is concealed in the space or chamber between the outer cover and the hand plate. When the outer cover is opened, as shown in Figs. 2 and 3, it is moved cross- 80 wise of the top 4, and is supported nearly in line with the back of the body portion, so that the writing tablet is in the path of the rays of light issuing from the electric light bulb. 85

The top 4 forms a stop which holds the outer cover at a slight angle with the body portion, so that the rays of light will fall on the writing tablet to the best advantage. When thus illuminated the tablet can be 90 written on, and the hand of the writer rests on the hand plate or inner cover 3, which need not be raised except to replace the battery when exhausted.

One terminal 24 of the lamp is preferably 95 connected with the battery by a contact spring 25, and its other terminal is preferably connected with a spring switch arm 26 which is secured to the casing by a rivet 27. The arm 26 has an inclined portion 28 near 100 its free end, or a V-shaped portion, and its free end has a contact edge 29. A block of insulating material 30 is secured to the top 4 of the casing, and a forked guide jaw 31 is secured to this block. The battery 15 has a 105 contact strip 32 which is slipped into engagement with the forked jaw 31. A slide- 110 able finger-piece or button 34 is provided, and engages with a longitudinal slot 35 in the side of the casing. This button has a projection 36 arranged adjacent to the inclined portion 28 of the switch arm 26, and

when the button is slid longitudinally in either direction it bears against one of the inclined portions and presses the contact edge 29 of the switch arm against the forked 5 jaw, and thereby completes the circuit so that the lamp is placed in action.

When the button is moved so that the projection passes beyond the inclined portion, the contact spring is held in constant engagement with the forked jaw. The pressure of the inclined portion of the spring switch arm moves the button in the reverse direction and opens the circuit automatically.

15 What I claim is:

1. A flashlight, comprising a casing provided with an inner plate at its front side which is adapted for use as a hand rest, an electric lamp bulb arranged at one end 20 of the casing, and a front cover for the casing pivoted to its end portion adjacent to the electric lamp bulb so that its inner surface is illuminated by the lamp when the cover is opened, said cover folding down 25 over the said inner plate when closed.

2. A flashlight, comprising a casing provided with an inner plate at its front side which is adapted for use as a hand rest, an electric lamp bulb arranged at one end of 30 the casing, a front cover for the casing pivoted to its end portion adjacent to the electric lamp bulb so that its inner surface is illuminated by the lamp when the cover is opened, said cover folding down over the 35 said inner plate when closed, and a detachable tablet or similar article secured against the inner surface of the front cover.

3. A flashlight, comprising a casing pro-

vided with an outer cover which is pivoted to its body portion so that the said cover 40 is moved crosswise of one end of the body portion when opened, an inner cover or hand plate also carried by the body portion and having a recess in its front face which forms a chamber between it and the outer 45 cover, a tablet or similar article attached to the outer cover and normally projecting into the said chamber, and an electric light bulb arranged at the said end of the body portion and adapted to illuminate the said 50 tablet when the outer cover is opened.

4. A flashlight comprising a casing provided with a cover having projecting arms at one end which straddle one end portion of the body and which are pivoted to its 55 sides to the rear of its front edge, so that the cover is moved crosswise of the end of the body when opened, and an electric light bulb arranged at the said end of the body portion.

5. A flashlight, comprising a casing provided with a cover having projecting arms at one end which straddle one end portion of the body and which are pivoted to its sides to the rear of its front edge, so that 65 the cover is moved crosswise of the end of the body when opened, a hand plate hinged to the said end portion of the casing body in front of the cover pivots and having flanges which slide between the sides of the 70 casing, and an electric light bulb arranged at the said end of the body portion.

In testimony whereof I have affixed my signature.

DAVID A. RUNNION.
